SAFETY SHIELD FOR CLIMBING IRON
GAFFSMerlin D. Weed and Percy A. Bennett,
Punxsutawney, Pa.

Application September 18, 1941, Serial No. 411,416

4 Claims. (Cl. 227—27)

This invention relates to a shield for the gaffs, spurs or spikes of climbing irons worn by linemen, and more particularly to a shield that is intended to be permanently attached to a climbing iron, and which can be quickly and easily moved from an inoperative position out of engagement with and away from the gaff to an operative position over the gaff to provide a scabbard or guard for the gaff when the climbing irons are not in use.

Due to the many serious and painful accidents resulting from wounds inflicted by the gaffs of climbing irons, many utility companies have regulations prohibiting the wearing of climbing irons when said irons are not actually in use; and this results in considerable loss of time as linemen must remove the climbing irons in order to engage in ground work so that the climbing irons are frequently applied and removed many times in the course of a day's work.

It is therefore a primary aim of this invention to provide a shield carried by the climbing iron and which can be quickly and easily applied over the spurs or gaffs thereof to prevent injury being inflicted by the gaffs to thereby eliminate the necessity of removing the climbing irons while linemen are engaged in ground work, thus effecting a material saving in the working time of linemen.

Still a further aim of the invention is to provide a shield which will also form a protection for the gaffs while the climbing irons are removed from the feet and legs and while being placed in truck compartments and otherwise handled, to eliminate accidents which frequently occur under such circumstances.

Still another object of the invention is to provide gaff shields which cannot be lost or misplaced and which will always be readily available when their use is desired, but which will not interfere with the normal use of the climbing irons to which they are connected.

Other objects and advantages of the invention will hereinafter become more fully apparent from the following description of the drawing, which illustrates a preferred embodiment of the invention, and wherein:

Figure 1 is a side elevational view showing a climbing iron equipped with the safety shield, and with the safety shield shown in full lines in an operative position, and in dotted lines in an inoperative position.

Figure 2 is a fragmentary edge view in elevation looking toward the outer side of the climb-

ing iron, and showing the shield in an operative position thereon.

Figure 3 is a longitudinal vertical sectional view taken substantially along the plane of the line 3—3 of Figure 2, showing the gaff and a portion of the climbing iron in elevation.

Figure 4 is a fragmentary side elevational view looking toward the lower portion of the inner side of the shield, and

Figure 5 is a fragmentary longitudinal substantially central sectional view of a portion of the shield shown latched in an inoperative position.

Referring more particularly to the drawing, wherein like reference characters designate like or corresponding parts throughout the different views, 10 designates generally a lineman's climbing iron including a gaff, spike or spur 11, which is disposed on the outer side of the lower part thereof, and which extends downwardly and outwardly and terminates in a pointed end 12. The gaff 11 is formed on the outer side of the bar portion 13, which engages the inner side of the foot and leg, and adjacent the lower end or foot engaging portion thereof. The climbing iron 10, including the parts 11 and 13, as previously described, and as illustrated in the drawing, form no part of the present invention, but are disclosed merely for the purposes of better illustrating the application of the safety gaff shield, designated generally 14, to a conventional climbing iron 10.

The safety gaff shield 14 includes an eye member 15 which is suitably attached to a portion 13, from which it projects from the outer side thereof. The eye member 15 is disposed above and near the upper, secured end of the gaff 11 and forms an anchor for one end of a contractile coil spring 16 which is fastened thereto at one end thereof. An elongated plate 17 is provided with an opening 18, adjacent one end thereof, in which the opposite, free end of the spring 16 is fastened for normally supporting the plate 17 in a depending position relatively to the eye member 15. The opposite, free end of the plate 17 is turned inwardly and back upon itself to form a loop portion 19. The terminal portion 20 of the loop 19 is disposed against the inner side of the plate 17 and may be suitably secured thereto as by means of soldering or welding. Directly below the secured end 20, the loop portion 19 is provided with a downwardly and outwardly inclined portion 21 which is provided with a triangular shaped opening 22, as best seen in Figure 4. The loop 19 is also provided with a

circular opening 23 in its outer side. A hook 24 projects from the outer side of the portion 13 above and spaced a substantial distance from the eye member 15. The hook 24 is provided with an upwardly extending substantially circular head 25, as seen in Figure 2, which is eccentrically disposed relatively to the shank of the hook, which extends outwardly from the member 13.

The spring 16, as shown in Figures 1, 2 and 3, and in dotted lines in Figure 1, is in each case shown stretched or under tension for urging the plate 17 toward the eye member 15. In Figures 1, 2 and 3, the plate 17 is shown in a depending position and with the pointed end 12 of the gaff 11 disposed in the loop 19 and with the triangular opening 22 engaging the gaff 11 near its pointed end 12, and at a point where the cross sectional shape of the gaff 11 corresponds to the shape of the opening 22. In dotted lines in Figure 1, and in Figure 5, the plate 17 is shown extending upwardly and away from the gaff 11 and adjacent the outer side of the portion 13, and with the shank of the hook 24 extending through the opening 23 and with its head 25 engaging against a portion of the inner side of the loop 19, above the opening 23. It will thus be apparent that in either of the two positions of the safety shield 14, as shown in Figures 1 and 5, the contractile spring 16 will urge the plate 17 in a direction to hold it in engagement either with the pointed end 12 of the gaff 11 or with the hook 24. With the safety shield 14 positioned, as seen in full lines in Figure 1 and in Figures 2 and 3, it will be readily apparent that the loop 19 will form a socket for enclosing the pointed end 12, and the plate 17 will be disposed on the outer side of the gaff 11 so as to shield the gaff to prevent it from causing injury. The safety shield 14 can be moved from this, its operative position, by a downward pull on the plate 17 to disengage the loop 19 from the gaff 11, after which the plate 17 and spring 16 can be swung upwardly to its dotted line position of Figure 1, and by expanding the spring, the opening 23 can be positioned so that the hook head 25 can be passed therethrough. By then releasing the plate 17 the spring 16 will retract sufficiently to position the loop 19, as seen in Figure 5, to prevent it from becoming accidentally disengaged from the hook 24, and to thus hold the shield 14 in an inoperative position away from the gaff so that the gaff 11 can be used in a conventional manner. By an upward and outward movement of the plate 17, it will be readily obvious that it can be disengaged from the hook 24 and swung downwardly, after which by a downward pull on the plate to stretch the spring 16, the opening 22 can be brought into a position to receive the point 12 of the gaff 11 and the spring 16 will urge the plate upwardly to retain the point 12 in the loop 19.

Various modifications and changes are con-

templated and may obviously be resorted to, provided they fall within the spirit and scope of the invention, as hereinafter defined by the appended claims, as only a preferred embodiment of the invention has been disclosed.

We claim as our invention:

1. A climbing iron gaff shield comprising a contractile coil spring adapted to be anchored to a climbing iron above the gaff thereof, a plate connected at one end thereof to the free end of the spring, said plate being provided with a socket adjacent its free end adapted to receive the pointed, free end of the gaff, said spring yieldably holding said socket portion in engagement with the gaff, and a hook mounted on the outer side of the climbing iron and above the anchored end of the spring for engaging the plate to hold it in an inoperative position on the outer side of the climbing iron and away from the gaff, and said spring acting to yieldably hold the plate in engagement with the hook.

2. A climbing iron gaff shield comprising a contractile coil spring, means for anchoring the spring at one end thereof to the outer side of a climbing iron above its gaff, an elongated plate attached at one end thereof to the free end of the spring and depending therefrom, the lower, free end of the plate being turned inwardly and back upon itself to form a loop portion, said loop portion being provided with an opening on its inner side, said opening being adapted to receive the pointed, free end of the climbing iron gaff, said spring and plate being disposed on the outer side of the climbing iron and being swingable to a position away from the gaff, and means for detachably holding the parts in said last mentioned inoperative position.

3. A device as in claim 2, said means including a hook projecting from the outer side of the climbing iron, and said plate being provided with an opening in its outer side for detachably receiving the hook, said spring acting to hold the plate in a position to prevent accidental disengagement of the hook from the plate.

4. A shield for climbing iron gaffs, comprising a contractile coil spring adapted to be anchored at one end thereof to the outer side of a climbing iron above its gaff, and an elongated plate connected at one end to the opposite end of the spring, the opposite end of the plate being turned inwardly and back upon itself to provide a loop having an opening in the back part thereof adapted to receive the pointed end of the gaff, said opening being sized to engage the gaff above and adjacent its point for holding the point within the loop and out of contact therewith, and said spring yieldably urging the loop upwardly and toward the gaff.

MERLIN D. WEED.
